UNITED STATES PATENT OFFICE.

LINWOOD B. AIKENS, OF ROCKLEDGE, FLORIDA.

TROLLEY-GUARD.

SPECIFICATION forming part of Letters Patent No. 761,637, dated June 7, 1904.

Application filed March 24, 1904. Serial No. 199,815. (No model.)

To all whom it may concern:

Be it known that I, LINWOOD B. AIKENS, a citizen of the United States, residing at Rockledge, in the county of Brevard and State of Florida, have invented certain new and useful Improvements in Trolley-Guards, of which the following is a specification.

This invention relates to trolley-guards, and has for its object the provision of improved means whereby a trolley-wheel will be restored to position upon the trolley-wire when it has been displaced therefrom.

In the accompanying drawings, Figure 1 is a front view, partly in section, of a trolley with my improved guard applied thereto in normal position. Fig. 2 is a side elevation. Fig. 3 is a front view showing my improved guard in operation.

Upon the end of a trolley-pole A, which extends upwardly from a car and is provided with a spring or other means for giving it an upward tendency, is a fork B, comprising arms 1 and 2, in which is secured a shaft 3. The usual trolley-wheel C for engagement with the wire D is rotatably mounted upon the shaft 3, and at the sides of the trolley-wheel the similar guards E and F are also rotatably mounted on the shaft 3. Washers 4 and 5 are placed between the trolley-wheel and the guards to prevent the guards from being rotated by reason of friction with the trolley-wheel when the apparatus is operating normally. Care should be observed, however, that the spaces between the wheel and guards are not wide enough to permit the trolley-wire to fall therein. Sleeves 6 and 7 on the shaft 3 bear against the inside faces of the fork and against the bosses 8 upon the guards E and F, thereby properly positioning the wheel and guards.

The guards E and F are precisely alike, so that a description of one will apply to either. Each of the guards is eccentrically mounted, and the farthest part 9 of the face of each from the shaft is the narrowest, measured by projections on its axis, and is inclined to the shaft. The inner edge of this part of the face is at least as great a distance from the shaft as the rim of the trolley-wheel, while the outer

edge is at a greater distance from the shaft than the inner one. Opposite the part 9 is the part 10, which is at the least distance from the shaft, is parallel thereto, and is the broadest part of the face. Preferably the part 10 of the face is at a less distance from the shaft than the rim of the trolley-wheel. Parts of the face intermediate the parts 9 and 10 so vary between them in width and inclination that the parts of the face merge into each other. Upon the outside edge of the face is a deflecting-flange 11. The center of gravity of each of the guards lies outside the shaft and on the side toward the face portion 9. They will therefore normally occupy positions as shown in Fig. 1, and the trolley-wire will normally lie in the groove of the trolley-wheel; as shown by full lines in that figure. If, however, the trolley-wheel should be displaced from the wire, so that the wire would occupy a relative position—for instance, as shown by the dotted lines in Fig. 1—the guard F would be turned by reason of its contact with the wire and the movement of the car and the wire coming in contact with the flange 11 the trolley-wheel would be gradually deflected toward the trolley-wire until the face part 9 became uppermost, as shown in Fig. 3, when the wheel would slide under pressure from the pole A into position on the wire. The center of gravity then lying above the shaft the guard would again assume the position of Fig. 1 in readiness for a similar operation. Obviously the guard E would operate in a similar manner to restore the wheel were it displaced upon the other side of the trolley.

While the preferred construction is shown in Figs. 1, 2, and 3, various other constructions might be employed, and although a flange has been shown on the outer edge of the guard in all the figures it may be desirable to omit it under certain conditions, and this can be done without departing from the spirit of my invention.

Without limiting myself to the precise construction and arrangement of parts shown, I claim—

1. The combination with a trolley-wheel, of

- a guard mounted to rotate eccentrically about the axis of said wheel, said guard having a face varying in width measured by projections on said axis, substantially as described.
- 5 2. The combination with a trolley-wheel, of a guard beside said wheel and mounted to rotate eccentrically about the axis of said wheel, said guard having a face varying in width measured by projections on said axis, and a 10 deflecting-flange extending along the edge of said face, substantially as described.
3. The combination with a trolley-wheel of a guard beside said wheel and mounted to rotate about the axis of said wheel, said guard 15 having a face varying in width measured by projections on said axis, and a deflecting-flange extending along the edge of said face, substantially as described.
4. The combination with a trolley-wheel; of 20 a guard mounted to rotate beside said wheel, said guard having a face varying in width measured by projections on its axis and a deflecting-flange extending along the edge of said face, substantially as described.
- 25 5. The combination with a trolley-wheel, of a guard mounted to rotate beside said wheel, said guard having a face varying uniformly in width from its narrowest portion to its widest portion and a deflecting-flange extending 30 along the edge of said face, substantially as described.
6. The combination with a trolley-wheel, of a guard mounted to rotate eccentrically beside said wheel, said guard having a face varying uniformly in width from its narrowest 35 portion to its widest portion and a deflecting-flange extending along the edge of said face, substantially as described.
7. The combination with a trolley-wheel, of 40 a guard mounted to rotate beside said wheel, said guard having a face varying in width and inclined to its axis at its narrowest part and a
- deflecting-flange extending along the edge of said face, substantially as described.
8. The combination with a trolley-wheel, of 45 a guard mounted to rotate eccentrically beside said wheel, said guard having a face varying in width and inclined to its axis at its narrowest part and a deflecting-flange extending along the edge of said face, substantially 50 as described.
9. The combination with a trolley-wheel, of a guard mounted to rotate eccentrically beside said wheel, said guard having a face varying in width, the narrowest portion being 55 at the greatest distance from its axis and inclined thereto, and a flange extending along the edge of said face, substantially as described.
10. The combination with a trolley-wheel, of a guard mounted to rotate eccentrically beside said wheel, said guard having a face varying in width, the narrowest portion being 60 at the greatest distance from its axis, and a flange extending along the edge of said face, substantially as described.
- 65 11. The combination with a trolley-wheel, of a guard mounted to rotate eccentrically beside said wheel, said guard having a face varying in width and inclined to its axis at its narrowest part, substantially as described.
- 70 12. The combination with a trolley-wheel, of a guard mounted to rotate eccentrically about the axis of said wheel, said guard having that portion of its face which is farthest removed from said axis of least width measured by 75 projections on said axis, substantially as described.

In testimony whereof I have signed my name to this specification in the presence of two subscribing witnesses.

LINWOOD B. AIKENS.
